UNITED STATES PATENT OFFICE.

JOHN SEDAJ, OF KENOSHA, WISCONSIN.

EXTENSIBLE TABLE.

1,048,596.

Specification of Letters Patent.

Patented Dec. 31, 1912.

Original application filed April 8, 1912, Serial No. 689,101. Divided and this application filed June 22, 1912. Serial No. 705,158.

To all whom it may concern:

Be it known that I, JOHN SEDAJ, a subject of the King of Hungary, but who have declared my intention of becoming a citizen of the United States, and a resident of the city of Kenosha, county of Kenosha, and State of Wisconsin, have invented certain new and useful Improvements in Extensible Tables, of which the following is a specification.

This invention relates to extensible tables, and more specifically to means for releasably locking adjacent sections of the table together, the present application being a division of my pending application Serial No. 689,101, filed April 8th, 1912, for extensible tables.

The object of my invention is the production of locking means as mentioned, which will be simple and economical in construction, means which may be readily and expeditiously manipulated to effect locking or unlocking of adjacent sections, and means which will be of high efficiency in use.

Other objects will appear hereinafter.

With these objects in view, my invention consists in the combinations and arrangements of parts hereinafter described and claimed.

My invention will be more readily understood by reference to the accompanying drawing forming a part of this specification, and in which—

Figure 1 is a perspective view of an extensible table embodying my invention, Fig. 2 is a partially sectional side elevation of the top portions of two adjacent extensible sections showing the same locked together, Fig. 3 is a fragmentary section through the adjacent edge portions of two connected extension sections, Fig. 4 is a fragmentary perspective view of the under side of one of the extension sections of the table, Fig. 5 is a perspective view of one of the locking hook members included in the construction, and Fig. 6 is a perspective view of one of the angular socket members coöperating with said hook members.

The preferred form of construction, as

illustrated in the drawing, comprises a table consisting of a main section 1 and a plurality of foldable sections which are adapted to be connected with the section 1 in order to extend the table, two extension sections only being shown in the drawing, 55 which are designated as 2 and 3. The extension sections 2 and 3 consist of table tops 4 and 4' respectively, at the under sides of which are hingedly secured supporting legs 5 and 5' respectively, arranged 60 adjacent corresponding edges of said table tops.

The table tops 4 and 4' are reinforced by means of longitudinally extending cleats 6 which are provided upon the under sides of 65 said table tops and secured thereto for alignment or registration by suitable securing devices 7. The section 3 is provided at one edge of the top 4' thereof with outwardly projecting engaging hooks 8 which are 70 adapted to engage sockets 9 formed in angular plates 10 which are secured upon three sides of each of the table tops, there being two socket members 10 provided at each edge of the table top for engagement with a 75 corresponding number of engaging members 8 provided upon the top 4'. The engaging members 8 are adapted, when engaged with the socket members 10, as clearly shown in Fig. 2, to securely fasten the sections together, unlocking of the members 8 in order 80 to disconnect the table sections, being effected only by elevating the end of the table top which carries the members 8 until the latter release the engaged edge portions 85 of the socket members, as will be readily understood.

In order to prevent accidental disconnection of the table sections, the cleats 6 at one edge of the top 4' of the section 3 90 are extended so that, when the engaging members 8 thereof are engaging sockets 9 of the section 2, as just described, said extended ends of said cleats will engage under the adjacent edge portion of the top 4 of section 2 and serve to yieldingly hold the table tops of said sections coplanar. With this arrangement, in order to disconnect

one section from the other, it will be required in the upward movement of the end of table top 4' carrying the members 8 (which movement is necessary in order to 5 effect disengagement of the members 8, as just described), to flex the adjacent portion of the table top 4', as clearly shown in Fig. 2. With this arrangement then the resiliency of the table top will serve as a means 10 of yieldingly holding the engaging members 8 of said top in locking engagement with the sockets 9 of the adjacent section.

The projecting ends of the cleats 6 in each section are formed with projecting pins 24. 15 which are adapted to engage recesses 25 provided in the opposite extremities of said cleats, as shown in the several views, and particularly Fig. 3, recesses 12' being also provided in the sides of cleats 6 for engagement by pins 11 in the event of a section being connected with one of the lateral edges of another section. The pins 11 and recesses 12 and 12' coöperate with the locking members 8 and the sockets 9 in securely fastening 20 the sections together. The top of section 3 is provided with socket members 10, as shown, so as to adapt the same for engagement by or connection with another extension section in the same manner as the sections 2 and 3 engage with one another.

While I have illustrated and described the preferred form of construction for carrying my invention into effect, this is capable of variation and modification without departing from the spirit of the invention. I, therefore, do not wish to be limited to the exact details of construction set forth, but desire to avail myself of such variations and modifications as come within the scope 35 of the appended claims.

Having described my invention, what I claim as new and desire to secure by Letters Patent, is:

1. An extensible table comprising a plurality of sections having tops adapted to be arranged edge to edge; means for detachably connecting adjacent sections, said means comprising a hook member projecting from one of the edges of the top of one of said 45 sections adapted to releasably engage a socket provided in the adjacent edge of the top of the other of said sections; and flexible cleats secured upon the under side of the top of one of said sections, corresponding 50 ends of said cleats projecting from the corresponding edge of said table top and engaging under the top of the other of said sections for yieldingly holding said hook member in locking engagement with said 55 socket, the flexibility of said cleats permitting of release of said hook member from said socket, substantially as described.

2. An extensible table comprising a plurality of sections having tops adapted to be

arranged edge to edge; means for detachably connecting adjacent sections, said means comprising a hook member projecting from one of the edges of the top of one of said sections adapted to releasably engage a socket provided in the adjacent edge of the 65 top of the other of said sections; flexible cleats secured upon the under side of the top of each of said sections, corresponding ends of the cleats of one of said sections projecting from the corresponding table top and 70 engaging under the top of the other of said sections for yieldingly holding said hook member in locking engagement with said socket, the flexibility of said cleats permitting of release of said hook member from 75 said socket, the cleats of one of said sections registering with and engaging against the cleats of the other section; and projecting pins provided at the ends of the cleats of one section engaging recesses provided in the adjacent portions of the cleats of the other section, substantially as described.

3. A sectional table comprising a plurality of sections having tops adapted to be arranged edge to edge; means for detachably connecting adjacent sections, said means comprising a locking member projecting from one of the edges of the top of one of said sections adapted to releasably engage a socket provided in the adjacent edge of the 90 top of the other of said sections, release of said locking member from said socket being effected by elevation thereof; flexible cleats secured upon the under side of the top of each of said sections, corresponding ends of the cleats of one of said sections projecting from the corresponding table top and engaging under the top of the other of said sections for yieldingly holding said locking member in locking engagement with said 95 socket, the flexibility of said cleats permitting of release of said locking member from said socket; and pins projecting from the projecting ends of said cleats adapted to releasably engage recesses provided in the 100 adjacent portion of the adjacent cleats, substantially as described.

4. A sectional table comprising a plurality of sections having tops adapted to be arranged edge to edge; means for detachably connecting adjacent sections, said means comprising a locking member projecting from one of the edges of the top of one of said sections adapted to releasably engage a 115 socket provided in the adjacent edge of the top of the other of said sections, release of said locking member from said socket being effected by elevation thereof; flexible cleats secured upon the under side of the top of one of said sections projecting from the corresponding table top and engaging under the 120 top of the other of said sections for yieldingly holding said locking member in lock- 125

ing engagement with said socket, the flexibility of said cleats permitting of release of said locking member from said socket; and pins projecting from the projecting ends of
5 said cleats adapted to releasably engage recesses provided in said ends of the cleats of the other section, substantially as described.

In testimony whereof I have signed my name to this specification in the presence of two subscribing witnesses.

JOHN SEDAJ.
